(57) CLAIM

I claim the ornamental design for a bottle with label, as shown and described.

DESCRIPTION

FIG. 1 is a front view of a bottle with label showing my new design, the broken lines being for illustrative purposes only and forming no part of my design;

FIG. 2 is a top view thereof;

FIG. 3 is a right side view thereof, the left side view being a mirror image thereof;

FIG. 4 is a rear view thereof; and,

FIG. 5 is a bottom view thereof.
